US00D382837S

United States Patent [19]

Haut et al.

[11] Patent Number: Des. 382,837

[45] Date of Patent: **Aug. 26, 1997

[54] ALL-TERRAIN STROLLER WITH SWIVEL WHEELS

[75] Inventors: Robert E. Haut, Paoli; Eric A. Schneider, Philadelphia; Steven Pancheri, Downingtown, all of Pa.

[73] Assignee: Graco Children's Products, Inc., Elverson, Pa.

[**] Term: 14 Years

[21] Appl. No.: 46,236

[22] Filed: Nov. 9, 1995

[51] LOC (6) Cl. 12-12

[52] U.S. Cl. D12/129

[58] Field of Search D12/128, 129; 280/642, 643, 644, 647, 648, 650, 658
